UNITED STATES PATENT OFFICE.

HENRY WALLIS, OF ST. LOUIS, MISSOURI.

IMPROVEMENT IN SCHOOL-SATCHELS.

Specification forming part of Letters Patent No. 135,254, dated January 28, 1873.

To all whom it may concern:

Be it known that I, HENRY WALLIS, of St. Louis, county of St. Louis and State of Missouri, have made a certain new and useful Improved School-Satchel; and I do hereby declare that the following is a full and true description thereof, reference being had to the accompanying drawing and to the letters of reference marked thereon.

The nature of this invention consists, chiefly, in providing with a school-satchel a lunch-box, pen- and-pencil case, inkstand, outside flexible straps for carrying larger sizes of books; also to the arrangement of the lid so as to open and close in front, securing and hooking the shoulder-straps; and to certain detail construction of parts—all of which will now more fully appear.

To enable those herein skilled to make and use my said improvements, I will now more fully describe the same, referring to—

Figure 1 as a perspective view; to Fig. 2 as a transverse sectional elevation; to Fig. 3 as a side view of turn-catch; to Fig. 4 as a plan section at line $x x$.

The body of the satchel consists of the back A, sides B B', and bottom C. D is a false top properly secured to the sides B B'. E are the shoulder-straps. F are flexible or rubber straps, arranged near the opposite ends and properly secured to the back of satchel. The top of the satchel I provide with a suitable metallic lunch-box, G, having a hinged lid, g. Said lid partly projects in front to completely close the front opening of the lunch-box, and is provided with a clasp, g¹, engaging a turn-catch, as shown in Figs. 1 and 2; also said lid can be provided with lock and key, as deemed preferable. The front face of lunch-box is covered by the material g², corresponding to satchel. The lunch-box G is secured, chiefly, to the satchel-top by the same rivets that secure the ends of the shoulder-straps and the rubber straps to the satchel. Therefore the one end of the respective straps E is riveted or fastened at e to the back A, next passed through a slot in said back; and both said strap ends are properly riveted to the under side of the false top D, as indicated in Fig. 2; this method of securing one end of each shoulder-strap being best adapted to carry

and sustain the entire weight of the satchel. The opposite ends of the shoulder-straps have a buckle, e¹, with which said ends can be secured in loop form. (See Fig. 2.) Further, the loop has a ring, e², which is retained in position by the leather clasp e³. The ends of the shoulder-straps can thus be adjusted as required by simply lengthening or shortening the play of the upper strap. To the bottom C of the satchel proper hooks c are attached, in which the rings of the shoulder-straps are hooked. The metal cover of the lunch-box need not be covered. The rubber bands or straps F are for the purpose of securing such larger class of books or articles as are not adapted to be stored inside the satchel. (See Fig. 2.) H is the proper lid of satchel, opening and closing in front.

In order that the lid H can be operated without any irregularity in its opening and closing action, I have surrounded the edges of said lid with metallic coverings h, which are simply metal strips folded over the edges of the lid and secured thereto, as shown in Figs. 1 and 2. The metal edge coverings also add strength and durability to lid, prevent its sagging, and especially enable me to pass a wire, h¹ through the top metal covering, (see Fig. 1,) thus forming a hinge for the lid to turn upon. The ends of the wire hinge h¹ are secured to the sides B B' of satchel. Further, in order that the opening and closing of the lid can be done with least inconvenience, I have provided the sides B B' and bottom C with turn-catches h² relatively positioned and secured. The lid H has suitable slots h³ through which the turn-catches pass, when lid closes, and being turned said catches adequately retain the lid closed. The turn-catches h² have their heads beveled, to more readily enter the slots of the lid, Fig. 3. Also, it will be noticed, that when the turn-catches are turned to admit the opening of the lid—if said catches are retained in same position—the lid can be immediately closed and at same time over all the catches; a simple turn movement of the head of the catches closes the lid. The bottom C of the satchel is hollowed, or otherwise mortised, to form a receptacle for a pen-case, C¹, and inkstand, C². The inkstand is of ordinary construction. The

pen pencil-case consists of a suitable square metal case, with hinged lid of sufficient size to store pens, pencil, ruler, and other school articles. Behind the pen-case C¹, and secured in the mortise part of bottom, is a suitable rubber spring, c¹, the object of which is to partly force out the pen-case and to more readily enable the operator to outdraw said case for use. The case C¹ is secured in the bottom C by a pin, c², which is of sufficient length to pass vertically through bottom C and the holes c³ of pen-case, as shown in Figs. 2 and 4. The inkstand C² can be retained in the bottom C by a detent-spring, c⁴, secured to said bottom, (see Fig. 4,) or can be similarly secured by a pin passing vertically through the parts. c⁵ is a spring-back of inkstand to facilitate the outdrawing of same. To the lid H is pivoted a curved metal strip, H', to prevent the contents in the satchel from undue play.

Having thus fully described my said invention, what I claim is—

1. The arrangement of a metallic lunch-box, G, with a satchel, as herein shown and described, as and for the purpose set forth.

2. The bottom C of a satchel, hollowed or mortised, as herein shown and described, as and for the purpose set forth.

3. An improved school-satchel, consisting of lunch-box G, shoulder-straps E, outside rubber bands F, pen pencil-case C¹, inkstand C², lid H, turn-catches h², satchel parts A, B, B¹, C, and D, all constructed to operate as and for the purpose set forth.

In testimony of said invention I have hereunto set my hand.

HENRY WALLIS.
